(57) **CLAIM**

The ornamental design for a hand held vacuum cleaner and base, as shown and described.

DESCRIPTION

FIG. 1 is a perspective view of a hand held vacuum cleaner and base showing our new design;

FIG. 2 is a front elevational view thereof;

FIG. 3 is a right-side elevational view thereof;

FIG. 4 is a rear elevational view thereof;

FIG. 5 is a left-side elevational view thereof;

FIG. 6 is a top plan view thereof; and,

FIG. 7 is a bottom plan view thereof.

The portions of the Figures shown in broken lines are not part of the claimed design and are for illustration only.
